UNITED STATES PATENT OFFICE

PETER GRAHAM MACGREGOR, OF PEQUANOCK, NEW JERSEY, ASSIGNOR TO PYRENE MANUFACTURING COMPANY, OF NEWARK, NEW JERSEY, A CORPORATION OF DELAWARE

FIRE EXTINGUISHER

Application filed July 11, 1928. Serial No. 291,872.

- My present invention relates to fire extinguishers and it has for its object to provide certain improvements in connection therewith relating principally to a valve mechanism for simultaneously controlling the passage of compressed air or gas from a pressure chamber to a fluid chamber and the escape of the fluid from the latter when the fluid is subjected to such pressure.
- 10 The invention has for its further object to provide a valve mechanism in which the valve heads may be controlled by a single actuator which serves to retract them simultaneously away from their valve seats and also serves 15 when the heads are in the closed position, to lock them against accidental disengagement.
- To these and other ends the invention consists in further improvements and arrangement of parts, all as will be more fully described, the novel features being pointed out 20 in the appended claims.
- In the drawings: Figure 1 is a side elevation of a fire extinguisher embodying my invention; Figure 2 is a plan view thereof; Figure 3 is a vertical central sectional view taken 25 on line 3^x—3^x of Figure 2; Figure 4 is a fragmental sectional view taken on line 4^x—4^x of Figure 2; Figure 4^a is a detail sectional view showing in detail the lower end of the pressure pump; Figure 5 is an enlarged horizontal sectional view taken on line 5^x—5^x of Figure 1; Figure 6 is a vertical sectional view taken on line 6^x—6^x of Figure 5; Figure 7 is a sectional view taken on line 7^x—7^x of Figure 30 5 showing the twin valves; and Figure 8 is a sectional view taken on line 8^x—8^x of Figure 5, showing the filler opening and cap. Similar reference numerals in the several figures indicate similar parts.
- 35 The extinguisher, herein shown, includes an outer or liquid chamber 10, having its lower end connected to a suitable base 11 and its upper end connected to the outer peripheral flange of a head 12 which is also provided 40 with an inner depending flange 13 to which the upper end of a pressure chamber 14 is secured, the lower end of the pressure chamber being closed, as shown, and spaced an appreciable distance from the bottom of the liquid chamber 10. Arranged within the 50 pressure chamber 14 is a vertically disposed pump cylinder 16 secured at its lower end within a cup-shaped member 17 on the bottom of the pressure chamber, its upper end projecting through the head 12 to which it is 55 suitably connected to form an airtight joint. Within the pump cylinder 16, is arranged a reciprocating piston 18, adapted to be operated by a piston rod 19, guided in a cap member 20, on the upper end of the pump cylinder 60 16 and having an air inlet port 21 formed therein. The outer end of the piston rod 19 carries a suitable handle 22. The pump, herein shown, is of the single acting type, its piston 18 being such that it permits air to 65 pass therearound on the outward stroke of the piston rod 19, and to be confined below the piston 18 upon expansion of the piston packing 23, when the piston is moved downwardly within the pump cylinder. A pressure tube 24 leads from the lower end of the pump cylinder 16 upwardly to the head 12, where it communicates with an air pocket such as a passage 25 leading from an air check 70 valve 26, of ordinary construction, the inner end of which opens into the pressure chamber 14. In order to permit the air valve 26 to be readily removed so that a new one may be 75 easily substituted, the head 12 is provided with a screw threaded opening 27 disposed 80 in alignment with the valve 26, and normally closed by a removable plug 28.
- Upon the head 12 is mounted a valve mechanism 29 adapted to control the flow of pressure from the air chamber 14 to the 85 liquid chamber 10 and also to control the escape of liquid from the latter through a nozzle tube 30, of the usual flexible type suitably connected to the head 12. A filler opening 31, is also formed in the head and pro- 90

vided with a removable screw-threaded plug 32. This opening is enlarged at its lower end to receive a short tube 33 which projects into the liquid chamber 10 so as to form an air pocket when the desired level of the liquid is reached to prevent the liquid from rising too high in the fluid chamber during the filling operation.

The valve mechanism 29 includes a housing 34 having a flange portion 34^a adapted to be suitably secured to the head 12, to form an air and liquid-tight union therewith. The housing 34 also includes a depending portion 35 which projects through an opening 36 in the head 12 and contains adjacently disposed parallel valve chambers which are internally screw threaded as indicated at 37 and 38. Within the chamber 37 is arranged a pressure valve head 39 and within the chamber 38 is arranged a liquid valve head 40, the former being provided with a pointed end adapted to engage a similarly shaped valve seat formed in an adjustable tubular plug 41 at the lower end of the chamber 37. The lower end of the liquid valve is preferably flat and seats upon an annular rib 42 carried by a tubular screw threaded plug 43 adjustably fitted in the extremity of the chamber 38. The valve heads 39 and 40 slide within the tubular gland nuts 44 and 45 which confine suitable packing in the upper ends of the chambers 37 and 38 and spaced an appreciable distance from the gland nuts 44 and 45, so as to form air and liquid spaces 46 and 47. The air space 46 communicates through a passage 48 with the liquid chamber 10, and leading from the liquid space 47 is an outlet or discharge pipe 49. This outlet pipe 49 passes around the flange 13 depending from the head 12, and terminates at its point of juncture with the outlet nozzle 30.

An important feature of the invention resides in the arrangement of the valve seats at the outer end of the valve chambers. These are made adjustable in the first instance to permit their being positioned properly in relation to the length of travel imparted to the valve heads by the actuating device. When once adjusted the valve seats are permanently secured in position. To this end the valve seats are formed on the plugs 41 and 43 which are threaded into the lower ends of the valve chambers. These plugs are preferably tubular to provide passages leading outwardly from the center of the seats and communicating with said passages are pipes 51 and 52; the former of which leads from the plug 41 and connects with the air chamber 14 and is provided with a reverse bend forming a trap therein. The tube 52 extending from the passage in the plug 43 reaches downwardly to a point adjacent the bottom of the fluid chamber 10 and may generally be termed a pick-up tube.

The housing 34 also comprises a circular

recess connecting the two valve chambers and contains the valve actuator. The outer portion of the wall of the recess is screw threaded, and fitted therein is a bearing plug 55, as shown in Figures 5 and 6, in which is journaled a cam shaft 56 projecting through a stuffing box 57 and carrying at its outer end a suitable hand wheel 58 for opening and closing the valves 39 and 40. The inner end of the cam shaft 56 carries a disk 59 journaled in the recess of the housing and having an eccentric cam slot 60 formed therein. In order that the valve heads 39 and 40 may be actuated simultaneously, they are connected together at their upper ends by a yoke 62, which rests upon the upper ends of said heads and has an offset portion 63 extending between the heads having lateral extensions or fingers 64 which engage in notches 65 formed in the contiguous sides of the heads near their upper ends. The yoke 62 is provided at one side with a projection such as a pin 66 which engages the cam slot 60 so that when the hand wheel 58 is rotated in a clockwise direction, as viewed in Figure 7, the valve heads are simultaneously lifted from their respective seats, and counter clockwise movement will project them again into closed position. Since it may often be necessary to seat the valve heads against pressure and it is desirable to hold them locked in closed position I provide the actuator with a second cam 61 the operating surface of which engages directly upon the top of the yoke 62 at its center. This cam is segmental in shape and its outer end engages the inner circular wall of the cylindrical recess in the casing to take the strain off the inner end of the shaft 56. The cam 61 is also shaped with reference to its axis of rotation that when the valve heads are closed its point of engagement with the yoke lies "off center" and effectively serves as a lock against the retraction of the parts.

In order to compensate for any irregularities in manufacturing and thereby insure simultaneous seating of the valves 39 and 40, the seats for these valves may be properly adjusted at the time of assembling the valve mechanism 33. In making such adjustment, the hand wheel 58 is set in closed position, and then the screw threaded plugs 41 and 43 are screwed into their respective openings 37 and 38 until their valve seats engage the heads 39 and 40. This adjustment may be easily made and when completed, the threaded plugs 41 and 43 are permanently secured in position, as by soldering. If during use, one of the valve seats, should become worn slightly more than the other, the effectiveness of the seals between the heads 39 and 40 and their respective seats is maintained due to the fact that the connection of the heads 39 and 40 with the yoke 62 is sufficiently flexible to permit slight relative movement be-

tween the heads 39 and 40 so that they may be forced into intimate sealing engagement with their respective seats.

In order to operate the extinguisher after filling the chamber 10 with a suitable fire extinguishing liquid pressure is supplied to the pressure chamber 14 by the pump herein shown, or it may be supplied from a suitable source, not shown, by removing the plug 28 and connecting such source with the valve 26. Inasmuch as the valve 26 functions as a check valve, insofar as the pressure chamber 14 is concerned, such pressure as is built up within the pressure chamber to the desired number of pounds, indicated by a suitable pressure gauge 68 carried by the head 12 and communicating with the pressure chamber 14, is effectively retained within the pressure chamber by the closed pressure valve 39 until it is desired to operate the extinguisher. By rotating the hand wheel 58 in a clockwise direction, as viewed in Figure 7, the valve heads 39 and 40 are lifted from their respective seats. Upon opening them communication between the pressure chamber 14 and the liquid chamber 10 is established by way of the pressure tube 51, tubular plug 41, air space 46 and the port 48. At the same time the pressure chamber 14 is opened to the liquid chamber 10, the latter is opened to the nozzle tube 30 by way of the pick-up tube 52, the tubular plug 43, the liquid space 47 and the discharge pipe 49, whereupon, the pressure supplied to the liquid forces it out of the nozzle tube 30 by way of the pick-up tube 52 and discharge pipe 49 as just described. In order to close the valve heads 39 and 40, the hand wheel 58 is rotated in a counter clockwise direction, as viewed in Figure 7, with the result that the cam 61, engages and cooperates with the yoke 62 to force the valve heads 39 and 40 downwardly into contact with their respective seats at or about the time the cam 61 assumes its position shown in Figure 7. Upon seating of the valve heads they may be urged into intimate engagement with their respective seats by moving the hand wheel 58 slightly further in a counter clockwise direction, as viewed in Figure 7, in which seated or closed positions they are locked by the cam due to its particular contour and its relation to the center of rotation thereof as will be readily understood.

While only one form of the invention is herein shown and described, it will be understood that various changes may be made without departing from the spirit of the invention and the scope of the following claims.

What is claimed is:

1. In a fire extinguisher of the type including pressure and liquid chambers, a valve mechanism for controlling the flow of pressure from the pressure chamber to the liquid chamber and for controlling the flow of liquid from the liquid chamber and comprising

a housing containing a pair of connected valve chambers, a pair of reciprocating valve heads, a yoke plate connecting them, a rotatable cam cooperating with said yoke plate to move said heads to closed positions and an auxiliary cam cooperating with said yoke plate to move said heads to open positions. 70

2. In a fire extinguisher of the type including pressure and liquid chambers, a valve mechanism for controlling the flow of pressure from the pressure chamber to the liquid chamber and for controlling the flow of liquid from the liquid chamber and comprising a housing containing a pair of connected valve chambers, a pair of reciprocating valve heads, a yoke plate connecting them, a rotatable cam cooperating with said yoke plate to move said heads to closed positions, a pin carried by said yoke, and a disk having a cam slot therein adapted to receive one end of said pin and cooperating therewith to move said heads to open positions. 80

3. In a fire extinguisher of the type including pressure and liquid chambers, a valve mechanism for controlling the flow of pressure from the pressure chamber to the liquid chamber and for controlling the flow of liquid from the liquid chamber and comprising a housing containing a pair of connected valve chambers, valve heads therein connected for simultaneous movement, a rotatable cam operating to move the valve heads to closed positions, adjustable tubular members disposed in alinement with said heads and provided with valve seats for said heads, a pressure pipe leading from said pressure chamber to one of said adjustable tubular members, and a pick-up tube leading from the interior of said liquid chamber to the other of said adjustable tubular members. 100 90

4. In a fire extinguisher of the type including pressure and liquid chambers, a valve mechanism for controlling the flow of pressure from the pressure chamber to the liquid chamber and for controlling the flow of liquid from the liquid chamber and comprising a housing having a pair of valve chambers serving as air and liquid spaces respectively, a pair of connected valve heads arranged for simultaneous movement within said chambers, a rotatable cam cooperating with said heads to move them to closed positions, tubular members disposed in alinement therewith forming valve seats, a pressure pipe for establishing communication between said pressure chamber and said air space through one of said tubular members, a pick-up tube for establishing communication between said liquid chamber and said liquid space through the other of said tubular members, and a discharge pipe leading from said liquid space to the exterior of said liquid chamber. 110 120 125

5. In a fire extinguisher of the type including pressure and liquid chambers, a valve mechanism for controlling the flow of pres- 130

sure from the pressure chamber to the liquid chamber and for controlling the flow of liquid from the liquid chamber and comprising a housing containing a pair of connected 5 valve chambers, a pair of reciprocating valve heads having notches formed therein, a yoke interlocking with said notches and a rotatable cam cooperating with said yoke for moving said valves longitudinally in the valve chambers.

10 6. In a fire extinguisher of the type including pressure and liquid chambers, a valve mechanism for controlling the flow of pressure from the pressure chamber to the liquid chamber and for controlling the flow of liquid from the liquid chamber and comprising a housing containing a pair of connected valve chambers, a pair of reciprocating valve heads having notches formed therein, 15 a yoke interlocking with said notches, a rotatable cam cooperating with said yoke for moving said valves longitudinally in the valve chambers, and an auxiliary cam cooperating with said yoke to lift said valves out 20 of engagement with their respective seats.

25 7. In a fire extinguisher of the type including pressure and liquid chambers, a valve mechanism for controlling the flow of pressure from the pressure chamber to the liquid chamber and for controlling the flow of liquid from the liquid chamber and comprising a housing containing valve chambers and a cam recess, a pair of valve heads in the valve chambers projecting into said cam recess, 30 packing material surrounding said valves at one end of the valve chambers, gland nuts confining said packing, adjustable tubular members disposed in alinement with said heads and provided with valve seats, said tubular members forming with said gland nuts air and liquid spaces in the valve chambers respectively, the former of which is in communication with said liquid chamber and the latter in communication with the exterior 35 of said liquid chamber, a pressure pipe leading from the pressure chamber to said air space through one of said tubular members, a pick-up tube for establishing communication between the liquid chamber and the liquid space through the other of said tubular members and a rotatable cam disposed within the cam recess and adapted to cooperate with the valve heads to move them into engagement with their respective seats.

40 8. In a fire extinguisher of the type including pressure and liquid chambers, a valve mechanism for controlling the flow of pressure from the pressure chamber to the liquid chamber and for controlling the flow of liquid 45 from the liquid chamber and comprising a housing containing valve chambers and a cam recess, a pair of valve heads in the valve chambers projecting into said cam recess, 50 packing material surrounding said valves at one end of the valve chambers, gland nuts

confining said packing, adjustable tubular members disposed in alinement with said heads and provided with valve seats, said tubular members forming with said gland nuts air and liquid spaces in the valve chambers respectively, the former of which is in communication with said liquid chamber and the latter in communication with the exterior of said liquid chamber, a pressure pipe leading from the pressure chamber to said air space through one of said tubular members, a pick-up tube for establishing communication between the liquid chamber and the liquid space through the other of said tubular members, a rotatable cam disposed within the cam recess and adapted to cooperate with the valve heads to move them into engagement with their respective seats, 70 an outlet pipe leading from said liquid space to the exterior of said liquid chamber, and an auxiliary cam adapted to cooperate with said valve heads for lifting them out of engagement with their respective seats.

90 9. In a valve mechanism for fire extinguishers, a housing comprising adjacent parallel chambers open at one end and having seats at the other end, valve heads cooperating with the seats and extending out of the chambers, a yoke resting upon the valve heads and attached thereto and provided with a laterally extending projection, an oscillatory operating member comprising a cam cooperating with the projection to move the valve heads relatively to their seats and a locking portion bearing against the yoke when the heads are in engagement with their seats.

95 10. In a valve mechanism for fire extinguishers, a housing having a circular recess and parallel chambers leading outwardly therefrom and having valve seats at their outer ends, valve heads cooperating with the latter and extending into the recess, a yoke resting upon the heads and connected thereto, and a disc journaled in the recess and cooperating with the yoke to move the valve heads 100 toward and from their seats.

110 11. In a valve mechanism for fire extinguishers, a housing having a circular recess and parallel chambers leading outwardly therefrom and having valve seats at their outer ends, valve heads cooperating with the latter and extending into the recess, and a yoke resting upon the heads and connected thereto and provided with a lateral projection, of a disc journaled in the recess at one side of the 115 yoke and provided with a cam slot cooperating with said projection.

120 12. In a valve mechanism for fire extinguishers, a housing having a circular recess and parallel chambers leading outwardly 125 therefrom and having valve seats at their outer ends, valve heads cooperating with the latter extending into the recess and provided with notches in their contiguous edges, a yoke in the recess extending over the ends of said 130

heads and having a portion projecting between them and engaging in said notches, a disc journaled in the recess of the housing cooperating with the yoke to reciprocate the 5 heads and a projection on the disc extending over the yoke and engaging the latter when the heads are seated to lock them in the closed position.

In testimony whereof, I have affixed my
10 signature to this specification.

PETER GRAHAM MacGREGOR.
